UNITED STATES PATENT OFFICE.

HELEN LEYNE, OF NEW YORK, N. Y.

DESIGN FOR A ROUGE BLENDER.

Application filed October 16, 1926. Serial No. 19,390. Term of patent 14 years.

To all whom it may concern:

Be it known that I, HELEN LEYNE, a citizen of the United States, and a resident of New York, borough of Manhattan, in the county and State of New York, United States of America, have invented a new, original, and ornamental Design for a Rouge Blender, of which the following is a specification, reference being had to the accompanying drawing, forming part thereof.

Fig. 1 is a plan view of a rouge blender, showing my new design.

Fig. 2 is an edge view thereof.

I claim:

The ornamental design for a rouge blender, substantially as shown.

HELEN LEYNE.
